US0D1105189S

(12) **United States Design Patent** (10) Patent No.: **US D1,105,189 S**
 Akey et al. (45) Date of Patent: ** Dec. 9, 2025

(54) **COLLABORATIVE ROBOT WELDING SYSTEM**(71) Applicant: **Vectis Automation, LLC**, Loveland, CO (US)(72) Inventors: **Andrew Steven Akey**, Windsor, CO (US); **Joshua Andrew Pawley**, Fort Collins, CO (US); **Douglas Phillip Rhoda**, Fort Collins, CO (US); **Aaron Lee Bailey**, Fort Collins, CO (US)(73) Assignee: **Vectis Automation, LLC**, Loveland, CO (US)(**) Term: **15 Years**(21) Appl. No.: **29/900,318**(22) Filed: **Aug. 19, 2023****Related U.S. Application Data**

(60) Continuation-in-part of application No. 29/860,206, filed on Nov. 17, 2022, now abandoned, which is a division of application No. 29/739,621, filed on Jun. 27, 2020, now Pat. No. Des. 975,151.

<https://vectisautomation.com/photo-gallery> (Year: 2023).*Primary Examiner — Patricia A Palasik(74) *Attorney, Agent, or Firm* — Glenn H. Lenzen; Elevated IP, LLC(57) **CLAIM**

The ornamental design for a collaborative robot welding system as shown and described.

DESCRIPTION

FIG. 1 is a rear perspective view of a collaborative welding system of the present design;

FIG. 2 is a top plan view thereof;

FIG. 3 is a rear elevation view thereof;

FIG. 4 is a left side elevation view thereof;

FIG. 5 is a front elevation view thereof; and,

FIG. 6 is a right side elevation view thereof.
